UNITED STATES PATENT OFFICE.

HUGH WATSON, OF WASHINGTON, DISTRICT OF COLUMBIA.

SAFETY DEVICE FOR ELEVATORS.

No. 910,247.

Specification of Letters Patent.

Patented Jan. 19, 1909.

Application filed May 29, 1908. Serial No. 435,798.

To all whom it may concern:

Be it known that I, HUGH WATSON, a citizen of the United States of America, residing at Washington, in the District of Columbia, have invented certain new and useful improvements in Safety Devices for Elevators, of which the following is a specification.

This invention relates to elevators and the invention may be termed a "safety attachment for elevator doors" in that it is designed to prevent the application of power to the hoisting mechanism until all of the doors are closed.

An object of this invention is to provide novel means which will effectually prevent movement of the elevator controller (that is the hand rope, lever, or other means of operating an elevator, switch, hydraulic valve or the like) so long as any one of a series of doors is open.

A further object of the invention is to provide novel means for opening the doors of an elevator shaft one at a time by means of mechanism for each door, which mechanism is made operative by devices on the car, preferably requiring the manipulation of the car attendant.

With the foregoing and other objects in view, the invention consists in the details of construction and in the arrangement and combination of parts to be hereinafter more fully set forth and claimed.

In describing the invention in detail, reference will be had to the accompanying drawings forming part of this specification wherein like characters denote corresponding parts in the several views, in which—

Figure 1, is a sectional view of an elevator shaft, showing the car and the mechanism embodying the invention applied thereto. Fig. 2, is a view in elevation of the door operating device coupled with a switch in a circuit of an electrical motor for driving the door operating mechanism and another switch for the circuit of the elevator controller; Fig. 3, is a sectional view on the line 3—3 of Fig. 2; Fig. 4, is a vertical sectional view on the line 4—4 of Fig. 2, omitting parts back of the disk engaged by the contacts; Fig. 5, is a detail view of a modification designed to be used in connection with hydraulic valves; and Fig. 6, illustrates further details thereof.

In these drawings A, denotes an elevator car having any preferred means for operating the switches for controlling the current

to the motor of the elevator hoisting mechanism, but as this particular feature forms no part of the present invention, it will not be described in detail.

The car is provided with a switch-closing lever *a*, pivoted thereon, and said lever has an anti-friction roller *a'*, engaging a movable member *B*, of the switch, which member *B*, is adapted to make electrical contact with the member *b*. Said members are connected by links *C*.

The door *a⁴*, of the elevator shaft has a flexible member *a²*, connected to it, which member is run over pulleys *a³*, and has its end connected to a drum *D*, on which it is wound to open the door.

A motor *E*, is geared to drive a shaft *F*, which preferably extends up the elevator shaft, and said shaft is designed to actuate each of the door-shifting devices, it being understood that one door shifting device will be provided at each floor of an elevator shaft. Each shifting device has a shaft *G*, suitably supported and connected by a gear *g*, to the shaft *F*, and as the shaft *F*, is rotated, motion is communicated to the shaft *G*. A disk *H*, is secured to rotate with the shaft *G*, but the drum *D*, is loosely mounted on said shaft *G*, and rotates therewith only when the electro-magnets *d*, which are mounted on the drum are energized and the cores thereof contact with the disk *H*. The cores of the magnets *d*, are so close to the disk *H*, that any movement of the drum *D*, longitudinally of the shaft *G*, is almost imperceptible. Disks *I* and *J*, are connected to rotate together and the disk *I*, is coupled to the drum *D*, by the brackets *i*. A contact disk *K*, is mounted on the shaft *G*, and is coupled to the disk *J*, by means of the pins *k*. When the magnets *d*, are energized and clutch the disk *H*, the several disks above-mentioned are caused to rotate with the shaft and as said disks have electrical contacts (to be presently described) the movement of said disks makes and breaks the circuit to the motor *E*, and to the control of the elevator motor.

The disk *K*, has a contact ring *K'*, and a segmental contact *k'*, on its face, said rings being in electrical contact with each other, and the space between the ends of the segmental contact *k'*, contains insulation *k²*. Brushes *L* and *L'*, engage the contact ring *K'*, and segmental contact *k'*, respectively, and said brushes have binding posts *l* and *l'*,

to which the conductors M and N, are connected. The conductor M, is secured to the stationary member b, of the switch and the conductor N, is connected to one brush of 5 the motor E.

The disks I and J, have peripheral conductors engaged by brushes i' and j', and said brushes have binding posts i² and j², respectively. A conductor O, is connected 10 to the binding post j², and to the stationary member b, of the switch heretofore described. The binding post i², has a wire P, connected to it, and said wire P is connected to the motor E, and to the feed wire Q.

15 The magnets d, are connected in series with the conductors d' and d², leading from the disks I and J, respectively. The drum D, carries a switch blade R, to engage the contacts r and r', from which the conductors 20 r² and r³, lead to the control of the motor for the elevator.

The conductors S and S', connect the brushes of the motor with the contacts s and s', and said contacts are engaged by the 25 switch blade R, when the drum is rotated in the direction of the arrow in Fig. 3. These parts are designed to short-circuit the motor E, and the relation of the parts is such that the switch blade makes electrical 30 connection with the contacts s and s', when the elevator door has moved a predetermined distance.

In operation, when the elevator car has 35 reached a floor, the lever a, is moved to force the switch-member B, into contact with the member b, circuit is established from the feed wire Q, through the brush i', to the magnets and to the brush j', and by the conductor O, to the switch member b, 40 thus establishing, as stated, a circuit through the magnets for the purpose of energizing the magnetic clutch. Simultaneously therewith, a current is established through the motor E, by the feed wire Q, conductors 45 N, M, switch b, B, and return wire p. The circuit just described is continued during the rotation of the disk K, and while the brushes are in engagement with the ring K', and segmental contact k', but said circuit is 50 broken when one brush engages the insulation k², between the ends of the segmental contact k'. A circuit having been established through the motor E, said motor will rotate the shaft F, thus driving the shaft 55 G, and with it, the drum D, since said drum is coupled by the magnetic clutch to the disk H. Initial movement of the drum disengages the switch blade R, from the contacts r and r', and hence the circuit is 60 broken to the control of the motor for operating the elevator and said motor will not be electrically connected again until the blade R, is restored to the position illustrated in Fig. 1. The winding drum continues 65 to rotate by power from the motor

E, until the switch blade R, engages the contacts s and s'. The conductors S and S', short-circuit the motor and this short circuit acts as a brake which immediately overcomes the momentum of the motor and arrests it. By reason of the mechanism just described, an elevator door is mechanically opened and said door is closed by the operator. As the door is closed, the flexible connection A², is unwound from the drum D, 70 thus rotating the drum on the shaft G, and with said drum the disk K, is rotated until the brushes L and L², are restored to contact with the members K' and k', respectively, thus reestablishing a circuit through 75 the motor E, when the switch member B, is caused to contact with the member b.

In applying a door-controlling device to hydraulic elevators, the hand rope U, is run over a sheave u, on a shaft T, and said shaft is provided with a friction brake in the form of a lever t, pivoted at t'. The lever has a weight V, adjustable on its end, and said lever also has a connection with a solenoid core W, working in the solenoid w. 90 In this application of the invention, the door-operating mechanism is the same as that heretofore described, except that the drum l^a, has the switch blade 2, engaging the contacts 3 and 4, and when the drum is rotated to open the door, the circuit through the conductors 5 and 6, (which are connected in series with each door-operating motor for the purpose of causing an interruption of the current through the solenoid if any door 95 of the elevator shaft is open) is interrupted. When the doors are closed the solenoid is energized and the brake is lifted, and hence the elevator may be operated, but if any door is open or partially open so that the 100 contact blade is out of engagement with the contacts, the solenoid will be demagnetized and the weight on the brake will prevent operation of the hand rope or controlling device of the elevator. In this form, the switch plate 2, engages the contacts 9 and 10 to close circuit through the conductors 7 and 8 designed to short circuit the motor as 105 previously explained.

I claim—

1. In combination with the doors of an elevator shaft, mechanism for moving each door, electrically controlled means for throwing the door operating means into and out of action, a motor connected to drive all 110 of the door operating mechanisms, means for controlling the electric current to the motor, and means for short circuiting the motor when the circuit to the motor is broken.

2. In combination with the doors of an 115 elevator shaft, a car mechanism for moving each door, an electric motor for driving the door operating mechanism, means for supplying current to the motor, means on the elevator car for controlling the current to 120

115

120

the motor, means for breaking the circuit to the motor, and means for simultaneously short circuiting the motor.

3. In combination with the doors of an elevator shaft, a car movable with relation to the doors, means for operating the doors, a motor independent of the car moving motor for actuating the door operating means, electrically controlled devices for connecting the door operating means with the actuating means, means for controlling the current to the motor, means for breaking the circuit to the motor, and means for simultaneously short circuiting the motor.
- 10 4. In combination with the doors of an elevator shaft, a car, a winding drum for each door, a flexible connection between each drum and the door to be operated by the drum, means for transmitting power to the drums, electrically controlled means for intermittently connecting the drums to the power transmitting means, and electrically controlled means for arresting the movement of the power transmitting means.
- 15 5. In an elevator, a shaft, a car, a series of doors, an independently operated device for moving each door, means for connecting

each door and its operating device, a motor independent of the car moving motor, means for connecting the first mentioned motor to 30 drive the door operating devices, means on the car for controlling the connection between the motor driven member and the door operating devices, and means for electrically braking the motor of the door operating devices.

6. In an elevator, a shaft, a car, a series of doors, an independently operated device for moving each door, means for connecting each door and its operating device, a motor 40 independent of the car moving motor, means for connecting the first mentioned motor to drive the door operating devices, means on the car for controlling the connection between the motor driven member and the 45 door operating devices, and means for short circuiting the motor.

In testimony whereof I affix my signature in the presence of two witnesses this 27th day of May, 1908.

HUGH WATSON.
